UNITED STATES PATENT OFFICE

2,538,429

HORIZONTALLY DIVIDED DOOR

Gordon M. Schantz, Allentown, Pa., assignor to
Mack Manufacturing Corporation, New York,
N. Y., a corporation of Delaware

Application March 27, 1945, Serial No. 585,172

7 Claims. (Cl. 160—206)

1

The present invention relates to doors for motor vehicles and embodies, more specifically, an improved form of folding door providing a minimum of obstruction when moved to its open position.

More particularly, the invention relates to folding doors for use on motor vehicles wherein a plurality of door sections are provided which, in a closed position, conform generally to the curved vehicle side wall in which the door is mounted.

An object of the invention is to provide a vehicle door having a plurality of sections extending both horizontally and vertically and articulated to form a complete closure when in the closed position.

A further object of the invention is to provide a vehicle door having horizontal as well as vertical hinge connections between the sections thereof.

Yet another object of the invention is to provide a vehicle door having a plurality of vertically spaced sections as well as a plurality of horizontally arranged sections, the vertically spaced sections lying in intersecting planes.

A further object of the invention is to provide, in a door of the above character, connecting means to pivot the several section thereof together to provide a complete closure.

Further objects of the invention will appear as it is described in greater detail in connection with the accompanying drawings, wherein

Figure 1 is a view in front elevation showing a door constructed in accordance with the present invention;

Figure 2 is an enlarged partial view in section showing the structure by means of which the edge of the door remote from the hinge is guided from open to closed positions;

Figure 3 is a view in end elevation showing the profile of the door and its relation to the vehicle step well;

Figure 4 is a view in section, taken on the line 4—4 of Figure 1, and looking in the direction of the arrows, showing the yielding non-metallic hinge structure between the upper and lower door panels;

Figure 5 is a top view of the door structure, the view showing the position of the door when it is in both the open and closed positions; and

Figure 6 is a view in section, taken on the line 6—6 of Figure 1, and looking in the direction of the arrows, this view illustrating the connection between the angularly disposed door operating shafts.

2

Referring to the above drawings, the side of a motor vehicle is illustrated at 10, being the profile of the side curved outwardly in accordance with the side surface conformation of a vehicle body when streamlined on its sides. In order that the door may occupy a minimum of space exteriorly or interiorly of the vehicle and conform closely to the shape of the side wall of the vehicle, the door is formed with portions that lie in intersecting planes. For example, Figure 3 illustrates the profile of the door in which the lower sections are illustrated generally at 11, and the upper sections generally at 12. These sections are connected together at the intersections of the planes thereof by means of a yielding hinge connection 13. Within the vehicle body steps 14 are provided in a suitable step well, in accordance with standard vehicle practice.

In order that the door sections may occupy as little space as possible and project as little as possible from the side of the vehicle when open, the door structure is preferably formed of two doors 15 and 16, as illustrated in Figure 1. Inasmuch as the structure of the doors 15 and 16 are identical, only one of them need be described.

With reference to door 15, it will be seen that it is formed of two upper sections 17 and 18, respectively, hinged together by a hinge 19, and two lower sections 20 and 21 hinged together by means of a hinge 22.

Section 17 is provided with hinged brackets 23, which are secured to an operating shaft 24, while section 20 is provided with similar hinge brackets 25, which are secured to an operating shaft 26. Shafts 24 and 26 lie in the planes of the respective upper and lower door sections and are connected together by means of a universal joint 27, shown in detail in Figure 6. Rotation of either shaft 24 or 26 about its axis thus rotates the other shaft about its axis, and the door sections 17 and 20 are thus swung upon the axis of the respective shafts 24 and 26. Any suitable means (not shown) for opening and closing the doors may be connected to either of the shafts and preferably to the shaft 24.

A continuous flexible closure strip 28 is secured to the outer edge of the sections 15 and 21, the strip preferably being of flexible material to permit the relative motion between sections 15 and 21 during rotation of the operating shafts 24 and 26. The flexible material 28 thus serves to secure the sections 15 and 21 together, and also serves as a gasket for sealing the door opening 55 when the doors are in closed position.

In order that the remote edges of the sections 15 and 21 may be guided from the closed to the open position, as shown in Figure 5, a bracket 29 is secured to the upper and outer portion of the section 15. Bracket 29 is formed with a pivot shaft 30 upon which a guide roller 31 is journaled. Guide roller 31 is received within a U-shaped track 32, secured to the upper face 33 of the door opening. In this fashion, when shaft 24 is operated to swing the door section 17 into the open position, illustrated in Figure 5, the hinge connection 19 between door sections 15 and 17 causes the guide roller 31 to move in the track 32 to turn the door section 15 into the open position illustrated in Figure 5, in which it lies in a plane parallel to the plane of the door section 17.

In order that a weather-tight connection may be preserved between the upper and lower door sections, the hinge connection 13 may consist of a flexible strip 34. This strip is illustrated in detail in Figure 4, and preferably is formed of a yielding non-metallic material such as rubber. The upper and lower extremities of the strip are received within clamp members 35 secured at 36 to the respective door sections. Clamp members 35 receive securing plates 37 and carrying pins 38 which are received in suitably positioned apertures 39 adjacent the edges of the flexible strip 34. In this fashion the flexible strip 34 is maintained in position regardless of the position of the door sections and, being flexible, permits the adjacent corners of the door sections to separate the necessary distance in swinging from the closed to the open position without impairing the weather-tight connection between the upper and lower sections.

While the invention has been described with reference to the specific structure illustrated in the accompanying drawings, it is not to be limited save as defined in the appended claims.

I claim:

1. A vehicle door comprising a plurality of vertically spaced sections, means to mount the sections to lie in intersecting planes when in the closed position, means to connect the sections hingedly at the adjacent edges thereof, operating shafts lying in the planes of the respective sections, and means to interconnect certain of said shafts operatively at the line of the intersection of said planes.

2. An articulated door comprising a plurality of lower sections lying in a common plane when in the closed position, means to hinge the sections together at the adjacent edges thereof, a plurality of upper sections lying in a common plane when in the closed position, the last named plane intersecting the first named plane, means to connect the upper and lower sections together hingedly at their adjacent edges, and means to move the sections from a closed to an open position in which the lateral sections lie in parallel planes.

3. An articulated door comprising a plurality of lower sections lying in a common plane when in the closed position, means to hinge the sections together at the adjacent edges thereof, a plurality of upper sections lying in a common plane when in the closed position, the last named plane intersecting the first named plane, means to connect the upper and lower sections together hingedly at their adjacent edges, operating shafts for the upper and lower sections, a universal

connection between the shafts, and means to guide the edges of the sections remote from the shafts at like sides of the sections to move the sections from a closed position to an open position in which the lateral sections lie in planes parallel to each other.

4. An articulated door comprising a plurality of lower sections lying in a common plane when in the closed position, means to hinge the sections together at the adjacent edges thereof, a plurality of upper sections lying in a common plane when in the closed position, the last named plane intersecting the first named plane, yielding non-metallic means to connect the upper and lower sections together hingedly at their adjacent edges, and means to move the sections from a closed to an open position in which the lateral sections lie in parallel planes.

5. An articulated door comprising a plurality of lower sections lying in a common plane when in the closed position, means to hinge the sections together at the adjacent edges thereof, a plurality of upper sections lying in a common plane when in the closed position, the last named plane intersecting the first named plane, yielding non-metallic means to connect the upper and lower sections together hingedly at their adjacent edges, operating shafts for the upper and lower sections, a universal connection between the shafts, and means to guide the edges of the sections remote from the shafts to move the sections from a closed position to an open position in which the lateral sections lie in planes parallel to each other.

6. An articulated door comprising a plurality of lower sections lying in a common plane when in the closed position, means to hinge the sections together at the adjacent edges thereof, a plurality of upper sections lying in a common plane when in the closed position, means to hinge the latter sections together at the adjacent edges thereof, said last-named plane intersecting said first-named plane, means to connect the corresponding upper and lower sections together hingedly at their adjacent edges, and means to move all of the sections from a closed to an open position in which the lateral sections lie in parallel planes.

7. An articulated door comprising a plurality of lower sections lying in a common plane when in a closed position, a plurality of upper sections lying in a common plane when in the closed position, the last-named plane intersecting the first-named plane, means to hinge the upper sections together at the adjacent edges thereof, means to connect the upper and lower sections together hingedly at their adjacent edges, and means to move all of the sections from a closed to an open position in which the lateral sections lie in parallel planes.

GORDON M. SCHANTZ.
